UNITED STATES PATENT OFFICE.

SOLON G. THOMAS AND ROCELL E. KIGHT, OF CORDELL, OKLAHOMA.

VENDING MACHINE.

Application filed September 10, 1921. Serial No. 499,596.

To all whom it may concern:

Be it known that we, SOLON G. THOMAS and ROCELL E. KIGHT, citizens of the United States, residing at Cordell, in the county of Washita and State of Oklahoma, have invented certain new and useful Improvements in Vending Machines, of which the following is a specification, reference being had to the accompanying drawings.

10 This invention relates to vending machines and more particularly to coin controlled vending machines, the principal object of the invention being to provide a simple and efficient device of this character in which articles of various kinds and characters may be dispensed upon depositing the proper amount of money and actuating the discharge plunger.

Another object of the invention is to provide a novel form of coin controlled lock which prevents actuation of the machine to discharge an article therefrom until a coin of the proper denomination is deposited.

A still further object of the invention is the provision of novel means for preventing clogging of the discharge valve and which assures the discharge of one article at a time and also controls the articles in the hopper so that at each retrograde movement of the valve an article will be forced into the discharge opening thereof.

Further objects of the invention will appear as the following specific description is read in connection with the accompanying drawings which form a part of this application, and in which:

Figure 1 is a front elevation with parts broken away;

Figure 2 is a vertical sectional view on the line 2—2 of Figure 1;

Figure 3 is a top plan view with the top removed;

Figure 4 is a horizontal sectional view on the line 4—4 of Figure 2;

Figure 5 is a detail vertical sectional view on an enlarged scale showing the adjustment of the gate valve; and

Figure 6 is an enlarged detail vertical section showing the engagement of the rack on the operating plunger with the feed roller.

Referring more particularly to the drawing, the casing generally indicated at 1 comprises a bottom 2, back 3, top 4, sides 5 and a front piece 6, a portion of which is formed

of a transparent panel 7. The front piece, as shown, extends from the top to a point slightly midway below the machine where it is cut away to provide an opening 8 by which the articles may be removed from the base or bottom 2, a retaining strip 9 being placed along the bottom to form a receptacle for the discharged articles.

As shown, the bottom of the casing is divided into separate compartments by a partition 10, and in the rear compartment thus formed we mount a suitable drawer 11 adapted to receive the money deposited after being discharged from the control mechanism.

Extending across the machine and secured to the side members 5 are strips 12 upon which is mounted a narrow platform 13 having slidably engaged with the upper surface thereof and with the upper surface of the strips 12 a valve 14, to the forward end of which is attached an operating plunger 15 projecting through the front piece 6 and through a reinforcing escutcheon plate 16, as shown. The valve is normally held in article receiving position by means of a spiral spring 17 engaged with the rear edge of the valve and with a strip 18, as shown in Figure 2.

Secured within the casing and arranged vertically is a partition member 19 dividing the upper portion of the casing into separate compartments 20 and 21, the latter of which forms a hopper for the reception of the articles to be dispensed and is provided with a removable inclined bottom 22 held in position by auxiliary side plates 23 removably mounted in the casing and forming abutment plates for the ends of the articles to be dispensed. These plates carry adjacent their lower ends the bifurcated arms 24 which have the pintles 25 of the roller 26 engaged in the bifurcation so as to have free rotation and vertical movement, but being held against any horizontal body shifting. The roller, as shown, rests upon the upper surface of the valve and is rotated thereby when the valve is reciprocated. In order that the roller may be positively operated to accomplish the results described hereafter, we preferably secure to the upper face of the plunger a rack 15^a which engages with the gear teeth 15^b formed in the roller and having the teeth flush with the outer face of the roller or slightly indented in order

that they may not interfere with the proper engagement of the articles with the roller. This roller, when the valve is pushed inwardly to discharge an article, will be rotated in the direction of the arrow so as to throw any articles resting thereagainst away from the opening 27 formed in the valve, and when the valve is moved outwardly under the action of the spring 17, the roller rotates 10 in a direction reverse to the arrow and has a tendency to force an article in the hopper into the opening so that it rests upon the platform 13. Carried by the partition 19 and the front piece 6 is a coin chute 28 which 15 registers with the opening 29 formed in a plate 30 carried by the front piece 6, and having thereon suitable indicia which indicates to the purchaser the amount to be deposited. At the inner end of the chute 28 the 20 same connects with a vertical chute 31 which has pivoted in its lower end a locking trigger 32 extending through the partition 19 and having a depending forward end arranged to normally engage a shoulder 33 25 formed on the upper surface of the valve 14. The trigger is held in shoulder engaging position by means of a spring 34 engaged with the rear end of the trigger and with a bridge piece 35 secured in the casing. Mounted on 30 the valve 14 immediately forward of the shoulder 33 is a coin actuating plunger 36 which extends upwardly and rearwardly over the valve and terminates in an inclined end 37 lying within the coin chute 31 and 35 in a position to engage a coin resting upon the rear upper edge of the trigger 32.

As shown in Figures 2 and 5, the rear wall of the coin chute 31 terminates considerably above the trigger 32 and has attached there- 40 to a gate valve 38 laterally offset at its upper end so that its forward face lies in a plane with the inner face of the rear wall of the chute. The upper end of the gate valve is laterally offset and slotted to receive the at- 45 taching and adjusting bolt 38^a. This valve is adjusted vertically so as to regulate the open- 50 ing between the lower end thereof and the trigger to accommodate the device to coins of the required denomination and to take up 55 any wear. As noted, the coin lodges against the lower end of the gate valve and the trigger 32 until dislodged, as will be hereinafter described, and when dislodged, falls into the chute 40 which is provided with an inclined bottom or lower end so as to discharge the 60 coin into the drawer or receptacle 11 pro- 65 vided for that purpose.

In order to prevent articles from collect- 60 ing upon the top of the roller and wedging 65 between the same and the front piece 6 when the valve is pushed inwardly, we preferably secure to the front suitable guard fingers 41 which overhang the roller, as shown, and are inclined to cause movement of the arti- 65 cles by gravity toward the opening 42 be-

tween the roller and a guard rib 43 secured upon the lower edge of the inclined bottom 22.

In the operation of the device, a coin of suitable denomination is pushed into the slot 70 29 from where it rolls down the chute 28 into the chute 31 until it contacts with the inclined end 37 of the plunger 36. It is then moved laterally by gravity until it assumes the position shown in dotted lines 75 in Figure 2, resting upon the upper surface of the trigger 32 and engaged with the lower edge of the gate valve 38. It will be noticed that in this position a coin of the proper de- 80 nomination is of too great a diameter to pass between the trigger and the lower edge of the gate valve until forced by the plunger 36. Upon operation of the plunger 15 in- 85 wardly, the plunger 36 first acts upon the coin to force the same through the restricted 90 opening formed by the lower edge of the gate valve 38 and the trigger 32, which causes a depression of the rear end of the trigger and an elevation of the forward end thereof out of the path of the shoulder 33. 95 Continued movement of the plunger 15 will carry the article in the opening 27 beyond the end of the platform 13 so that it will drop into the receptacle formed by the parti- 100 tion 10 and the rib 9. In this movement of the valve, all articles held in the opening 42 will be carried away from the opening 27 by the action of the roller and when the plunger 15 is released and the valve is re- 105 turned to normal position, the roller will continue to carry an article through the opening 42 into the opening 27 where it rests upon the platform 13. In this re- 110 tracted movement of the valve, the forward end of the trigger slides over the attaching flange of the plunger 36 until the valve al- 115 most reaches its outermost position when the trigger will snap off the valve and lie in the path of the shoulder. Any operation of the plunger without there being a coin of 120 the proper denomination in the position shown in Figure 2, will result in the trigger coming into contact with the shoulder 33 so as to effectually lock the plunger against 125 further inward movement and discharge of the article contained in the opening 27. It is, of course, understood that the slot 29 is of such length and width that it will not re- 130 ceive a coin larger than that required to operate the machine and that if a coin of 135 smaller denomination than that required to operate the machine is inserted, it will pass through the opening defined by the lower edge of the gate valve 38 and the upper edge of the trigger 32, rolling off the inclined end 37 of the plunger into the chute 40 where it will be discharged into the recep- 140 tacle 37 without operating any of the parts.

The machine illustrated herein is adapt- 145 ed particularly to dispense pencils, but we 150

wish it clearly understood that with the present form of mechanism which may be changed to suit conditions in practice without departing from the spirit of the invention, we may dispense various types of articles, as will be readily understood, and the size of the parts may be such as to accommodate the machine for these articles and for various denominations of coins or checks.

10 What we claim is:

1. In a vending machine, a casing, an article dispensing valve slidably mounted therein, a coin chute having an opening, a valve locking trigger pivoted in the coin chute and extended through the opening to prevent passage of a coin of proper denomination, said trigger normally preventing a discharge movement of the valve, and a plunger carried by the valve and operated 15 in the discharge movement thereof to force a coin through said opening and throw the trigger out of locking position.
2. In a vending machine, a casing, an article dispensing valve slidably mounted 20 therein, a coin chute having an opening, a trigger pivoted in the coin chute and ar-

ranged to restrict said opening, means for normally holding the trigger in position to lock the valve against discharge movement, a plunger carried by the valve and operated 30 in the discharge movement thereof to force a coin through said opening and thereby throw the trigger out of locking position, said plunger having means to guide the coin toward the restricted opening.

3. In a vending machine, a casing, an article dispensing valve slidably mounted therein, a coin chute having an opening, a trigger pivoted in the coin chute and arranged to restrict said opening, means for 40 normally holding the trigger in position to lock the valve against discharge movement, and a plunger carried by the valve and operated in the discharge movement thereof to throw the trigger out of locking position, 45 said plunger having an inclined end positioned in the chute adapted to guide a coin to the restricted opening.

In testimony whereof we hereunto affix our signatures.

SOLON G. THOMAS.
ROCHELL E. KIGHT.
